(57) **CLAIM**

The ornamental design for a scanbody, as shown and described.

DESCRIPTION

FIG. 1 is a upper perspective view of a scanbody.

FIG. 2 is a lower perspective view of the scanbody of FIG. 1.

FIG. 3 is top view of the scanbody of FIG. 1.

FIG. 4 is a bottom view of the scanbody of FIG. 1.

FIG. 5 is a left side view of the scanbody of FIG. 1.

FIG. 6 is a right side view of the scanbody of FIG. 1.

FIG. 7 is a front view of the scanbody of FIG. 1; and,

FIG. 8 is a back view of the scanbody of FIG. 1.

The broken lines shown in the figures represent portions of the scanbody that form no part of the claimed design.
